ATTORNEY.

UNITED STATES PATENT OFFICE.

JOHN U. NICHOLSON, OF STEUBENVILLE, OHIO.

DESIGN FOR A ROUGH-FACED BRICK.

48,983.

Specification for Design.

Patented May 2, 1916.

Application filed December 30, 1915. Serial No. 69,489. Term of patent 7 years.

To all whom it may concern:

Be it known that I, JOHN U. NICHOLSON, a citizen of the United States, residing at Steubenville, in the county of Jefferson and State of Ohio, have invented a new, original, and ornamental Design for a Rough-Faced Brick, of which the following is a specification, reference being had to the accompanying drawing, in which the figure is

a perspective view of a rough-faced brick embodying my invention.

I claim:

The ornamental design for a rough faced brick, as shown.

JOHN U. NICHOLSON.

Witnesses:

D. M. GRUBER,
KATHERINE CONNOR.
